Primary Examiner — Kevin K Rudzinski(74) *Attorney, Agent, or Firm* — QuickPatents, LLC;
Kevin Prince(57) **CLAIM**

I claim the ornamental design for a T-shirt with accessories, as shown and described.

DESCRIPTION

FIG. 1 is an exploded perspective view of a T-shirt with accessories showing a pocket for displaying a cell phone, a removable spinner with snap-on accessories, and a logo tag; FIG. 2 is a front perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; and, FIG. 8 is a bottom plan view thereof.

The dot-dash broken lines in FIGS. 1-3 represents a boundary of the claimed design. The broken lines showing remaining portions of the T-shirt in FIGS. 1-8, a cell phone in FIGS. 1-2, and graphics applied to the spinner and logo tag depict environmental matter and form no part of the claimed design.
